Primary Examiner — Jeffrey D Asch*Assistant Examiner* — Rebekah A Caruso(74) *Attorney, Agent, or Firm* — Banner & Witcoff, Ltd.(57) **CLAIM**

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The uneven-length broken lines immediately adjacent to the shaded area define the bounds of the claimed design, and form no part thereof. The two unshaded regions within the shaded area that are demarcated by broken lines form no part of the claimed design. The even-length broken line within the shaded area represents a feature that forms no part of the claimed design. The uneven-length broken lines showing the remainder of the shoe are for environmental purposes only and form no part of the claimed design.
